WILLIAM DUNMORE LOVEDAY, OF EASTBOURNE, ENGLAND

SPRING WIRE CLIP FOR NEWSPAPERS AND THE LIKE

Application filed March 31, 1931, Serial No. 526,719, and in Great Britain April 1, 1930.

The object of this invention is to provide an improved form of clip which can be easily applied to a number of sheets of paper so as to hold them together firmly and more especially at the fold of a number of newspaper or other sheets so as to keep the several sheets in proper position with their folds parallel and thus enable the sheets to be handled with comfort.

10 A clip according to the invention comprises a length of suitable spring wire bent back upon itself with the two end portions extending in opposite directions, and terminating respectively, at or about, and beyond the bend 15 or loop of their companion bent back portions, the bent back portions running substantially parallel and under their spring action pressing against each other and effecting a primary grip, an additional grip being obtained between the longer bent back portion and both the other portions. The shorter end portion and the portion intermediate of the bent back end portions are close together so that the long end portion rests on them 25 and the bend or loop beyond which the long end portion extends is canted outwardly therefrom so as to act as a guide for the sheets when the clip is being applied to them. The arrangement is such that by end pressure in 30 the direction in which the long portion extends the clip can be easily passed over a number of newspaper or other sheets so that they will be firmly gripped between the long portion and the other two portions of the clip 35 without damage or serious creasing. Preferably the bends are made in directions at right angles to each other.

Figs. 1 and 2 of the accompanying drawings are views at right angles to each other, 40 of a clip according to the invention.

The clip consists of a piece of spring wire bent as shown to form three portions or bars 1, 2 and 3 which lie close alongside each other and of which the bar 3 is the longest; each 45 of the bars 1 and 3 is set so that it springs into contact with the other two bars, and that the bars 1 and 3 are substantially parallel as seen in Fig. 2 and in contact. The bends at 1^a and 1^b are made at right angles to each 50 other and the bend at 1^b is canted outwards to

serve as a guide for the insertion of the sheets between the bar 3 and the bars 1 and 2, which latter are brought close together so that the bar 3 rests on them and is thereby prevented from being caused by its spring action to 55 descend into the bend 1^b which stands well away from the bar 3 and facilitates insertion of the sheets of paper. As seen in Fig. 1 the bar 3 lies between the bars 1 and 2 and as seen in Fig. 2 the bar 1 lies between the bars 2 and 60 3 and stops just short of the bend 1^a. On the clip being applied to sheets of paper, the bars 1 and 3 effect the primary grip throughout the greater part of their length where they run in contact and substantially parallel to 65 each other, but as the thickness of the paper sheets is increased, the bar 3 presses the paper into the groove between the bars 1 and 2 and an additional spring grip on the paper is obtained between both the bars 1 and 2 and the 70 bar 3, and accidental lateral movement of the clip along the sheets is prevented; as the bars 1 and 3 are forced in opposite directions they will continue to be more or less parallel as viewed in Fig. 2 and give a longitudinally 75 extensive grip on the sheets which resists lateral and swinging movements without interference with the easy removal of the clip when desired. What may be termed a "compensating action" takes place between the bar 3 and the other or double bar portions of the clip when applied to articles or papers of a body thickness greater than at the edge to or over which the clip is applied. This action causes the parts to draw or tend to draw closer together after initial spreading, as the clip is pushed to bring its bend 1^a against the edge. This action will be observed plainly by passing a pocket knife blade between the bar 3 80 and the other or double bar portions, from the 85 canted bend to the other.

What I claim is:—

1. A paper clip, comprising a length of spring wire bent back and forth upon itself with the two end portions thereof extending 90 in opposite directions substantially parallel and in contact with each other, and with one of said portions terminating at or about one of the bends and the other projecting beyond the other of the bends; said one and shorter 100

of the end portions being disposed close to the intermediate portion of the wire and there-with canted outwardly near the bend there-between from which said other of the end portions projects, and said other or longer end portion being disposed centrally of and underlying the last-mentioned bend but held from entering or springing thereinto by contact with said shorter end and intermediate portions in rear of said bend, whereby to therewith provide a guide and easy slippage over the paper to be clipped.

2. A paper clip, comprising a length of spring wire bent back and forth upon itself with one end portion longer than the other and the two extending in opposite directions substantially parallel to and contacting each other; the bends between said end portions and the intermediate portion of the wire being in planes substantially normal to each other, and said longer end portion being pressed against the shorter end and intermediate portions short of the bend therebetween; and the last-mentioned bend being canted outwardly so as to stand clear of the longer end portion.

3. A paper clip, comprising a length of spring wire bent back and forth upon itself with one end portion longer than the other and the two extending in opposite directions substantially parallel to each other; the bends between said end portions and the intermediate portion of the wire being in planes substantially normal to each other, the bend connecting the intermediate portion and the shorter end portion being canted, the two end portions by spring action pressing against each other in a gripping contact along the greater part of their length, and said longer end portion being pressed also against said intermediate portion short of the last-mentioned bend and thereby held against entering the same.

Signed at London, England, this 18th day
of March, 1931.
